DESIGN FOR A CHAIR

Willard H. Bond, Jr., East Grand Rapids, Mich.,
assignor to American Seating Company, Grand Rapids, Mich., a corporation of New Jersey

Application May 8, 1935, Serial No. 56,723

Term of patent 7 years

To all whom it may concern:

Be it known that I, Willard H. Bond, Jr., a citizen of the United States, residing at 605 Greenwood St., East Grand Rapids, in the county of Kent and State of Michigan, have invented a new, original, and ornamental Design for a Chair, of which the following is a specification, reference being had to the accompanying drawings, forming a part thereof, in which:—

The figure is a perspective view of the chair, the distinguishing, essential and dominating feature or characteristic of the design being the end standards, the unimportant features of the design being the form or contour of the chair back, seat and arm rests.

I claim:

The ornamental design for a chair as shown and described.
